UNITED STATES PATENT OFFICE.

SAMUEL APPLETON, OF BRISTOL, PENNSYLVANIA.

DESIGN FOR A PRESS-BOARD FOR STOCKINGS.

SPECIFICATION forming part of Design No. 15,137, dated July 15, 1884.

Application filed May 28, 1884. Term of patent 7 years.

To all whom it may concern:

Be it known that I, SAMUEL APPLETON, a citizen of the United States, and a resident of Bristol, Bucks county, Pennsylvania, have invented a certain new and original Design for a Press-Board for Stockings, of which the following is a specification.

My design for a press-board for stockings is fully illustrated in the accompanying drawings, which show side views of two forms of board embodying the design. The board has a foot-portion, *a*, ankle *b*, and calf *d*, similar to an ordinary press-board; but above the calf the board is contracted in width at *e*, so as to 15 form the effect of a garter. The contraction

may be formed by recessing both edges of the board, as in Figure 1, or one edge only, as in Fig. 2.

I claim—

The design for a press-board for stockings, 20 said design comprising the foot, ankle, calf, and contracted portion *c* above the calf, as shown and described.

In testimony whereof I have signed my name to this specification in the presence of two 25 subscribing witnesses.

SAMUEL APPLETON.
